UNITED STATES PATENT OFFICE.

HENRY A. SIEBERT, OF DETROIT, MICHIGAN.

DESIGN FOR A LOOP-RADIATOR.

SPECIFICATION forming part of **Design No. 26,203**, dated **October 20, 1896**.

Application filed **May 7, 1896**. Serial No. **590,626**. Term of patent **7 years**.

To all whom it may concern:

Be it known that I, HENRY A. SIEBERT, of Detroit, in the county of Wayne and State of Michigan, have invented a new and useful improvement in a Design for Loop-Radiators, of which the following is a specification.

My invention consists in a design for loop-radiators hereinafter described and claimed.

The accompanying photograph shows a perspective view of a radiator composed of assembled loops.

In my design the loops are made of cast-iron and are substantially in the form of an elongated ring in cross-section. They are panelled or recessed on their sides and the panel in the outer side of the end loop is ornamented with scrollwork in Italian renaissance style, reaching from top to bottom. The front edge

of each loop is fluted or ribbed from top to bottom and is ornamented with scrollwork for a short distance from the top down and from the bottom up. The upper edge of each loop is fluted in arch form and is ornamented with scrollwork. The lower edge of each intermediate loop is approximately V-shaped and the lower edge of the end loops is prolonged downward at front and rear into legs, which are ornamented.

What I claim as my invention, and desire to secure by Letters Patent, is—

The design for a radiator substantially as herein shown and described.

HENRY A. SIEBERT.
